NECKTIE AND HOLDER ASSEMBLY

Kenneth A. Lambrechts, St. Louis, Mo.

Application April 4, 1947, Serial No. 739,295

2 Claims. (Cl. 2—153)

1

This invention relates to an assembly of a necktie of particular construction and a holder therefor, the principal object of the invention being to supply such a combination which will hold a necktie of the style known as a "four-in-hand" in place around the wearer's neck and eliminate the necessity of subsequent adjustments, once the tie has been properly positioned.

As every wearer of neckties knows, even when a tie has been carefully tied and accurately adjusted, it is inclined to slip and become loosened, and in order to avoid an untidy appearance it must be more or less frequently adjusted. This is not only annoying to the wearer, but also from much handling the knot of the tie soon becomes soiled, thus necessitating frequent cleaning of the tie. Through the use of my assembly these disadvantages are overcome, since the tie cannot slip out of place or get loose after it has been donned, and thereafter needs no further handling until the wearer takes it off.

It is a well known fact that in a four-in-hand tie the knot is the first part of the tie to become soiled, often while the remainder of the necktie is still clean, and it is another advantage of my assembly that through its use the portion forming the knot can be replaced with a fresh section of the material of which the tie is made while the remainder of the original tie can still be used.

In the drawings—

Fig. 1 is a perspective view of the outer member of my necktie holder.

Fig. 2 is a perspective view of the inner member of my necktie holder, showing the means for reception of the tie.

Fig. 3 is a perspective view of a four-in-hand necktie especially constructed for engagement with my necktie holder.

Fig. 4 is a perspective view showing the replaceable portion of my especially constructed necktie.

Fig. 5 is an elevational rear view illustrating the first step in assembling my necktie and the holder therefor.

Fig. 6 is an elevational rear view illustrating the necktie and holder therefor in assembled condition.

Fig. 7 is a rear elevational view illustrating the necktie and holder assembly as it appears in operative position.

Fig. 8 is an enlarged, cross-sectional view taken on line 8—8, Fig. 7, illustrating particularly the engagement of the necktie and holder.

Fig. 9 is a cross-sectional view taken on line 9—9, Fig. 8.

2

As mentioned before, this invention comprises an assembly consisting of a necktie holder and a four-in-hand tie especially constructed for use with such holder. I will first describe the holder, which consists of two separate parts, the first part A of which is an inverted, conical, truncated member having a wall 1, which is partly cut away, leaving free longitudinal edges which are bent at right angles to the wall 1 to form flanges 2 and 3. 5 That portion of the wall 1 which is opposite the cut-out is dented to form a small, inwardly extending bulge 4. The member just described may be made of any suitable material which is almost rigid, but may have a very slight degree of resilience, for instance, hardened aluminum.

As said before, the holder includes a second, separate part B, and this part has substantially the same general inverted, truncated, conical shape as the first part A just described, having 10 an open space to correspond to the cut-out of the first part, but is of somewhat smaller dimensions so that it will fit into the first part A, as will be later set out. This second part B is integrally formed of a section of resilient material bent 15 back upon itself, as at 5, to form an outer wall 6 and an inner element 7 which is curved in a direction generally parallel with the outer wall 6, said wall 6 having a free longitudinal edge 8. At its free end the element 7 is of such length as to 20 form an extension 9 across the opening in the wall of the part B, and the wall 6 and element are so positioned with respect to each other as to leave 25 a space 10 therebetween. The wall 6 and the element 7 are each dented to form bulges 11 and 12, respectively, therein (Fig. 9) which are similar to the bulge 4 in the wall 1 of the first described part A of the holder, and as will be later shown, all three of the bulges 4, 11, and 12 are in 30 registration when the holder is in use. The part 35 B of the holder as just described is clearly illustrated in Fig. 2.

Having completed the description of my necktie holder, I will now proceed to describe the especially constructed tie designed to be used therewith. The ordinary four-in-hand tie, as is well known, has one end of greater width than the opposite end, and its longitudinal edges extend in straight, diagonal lines from end to end 45 of the tie, so that the wide and narrow portions thereof merge gradually. My especially constructed tie differs from this formation in that it has an offset 13 in each of its longitudinal edges, these offsets being diametrically opposite each 50 other to effect an abrupt junction between the 55

wide portion 14 and the narrow portion 15 of the tie, all of which is illustrated in Fig. 3.

I provide a separate section 16 of the same material as the tie just described, this section having diagonally extending, straight side edges 17, its top edge 18 being bowed outwardly and its bottom edge 19 so curved as to be parallel with the top edge 16. Since the section 16 will form the knot of the completed tie, it is of such dimension from top to bottom as necessary for this purpose. The section 16 is plainly shown in Fig. 4 of the drawing.

In operation the procedure is as follows:

The wide portion 14 of the necktie is inserted into the part A so that the offsets 13 come approximately to the upper edge of said part or just slightly below it, but do not extend above the edge, and below said part A the remainder of the wide portion 14 of the tie flares, as shown in Fig. 5.

The separate section 16 of the tie is now applied to the outer surface of the wall 1 of the part A with its curved, upper edge at the top of said part, the section 16 being of such dimension that said curved, upper edge 18 extends very slightly above the part and its bottom, curved edge 19 extends very slightly below the part A. The material adjacent the side edges 17 of said section 16 are then turned in over the flanges 2 and 3 and extend into the part A.

The resilient part B is then pushed into the part A in such a manner that its bent edge 5 underlies the flange 2 and its free edge 8 underlies the flange 3, and the ends of the section 16 of the tie adjacent its edges 17 are caught and tightly gripped between said flanges and the edges 5 and 8, respectively, of the part B.

The parts are now in the position shown in Fig. 6, and the tie is ready to be donned by the wearer, and this is accomplished in the following manner:

The narrow portion 15 of the tie is placed about the wearer's neck rather loosely, and he grasps the holder and the parts engaged therewith in his left hand and the narrowest part of the portion 15 in his right hand, and then inserts the lefthand edge of the portion 15 into the space 10 of the part B and threads it through this space around the element 7 until said lefthand edge rests within the bend 5, and the portion 15 which has been inserted into the space 10 lies between the wall 6 and the element 7 of the part B. The various elements of the invention are now in the position shown in Fig. 7, and it remains only for the wearer to adjust the knot to the correct position, which he does by holding the portion 15 which depends below the holder in one hand and pushing up the knot with the other hand, it being understood that the knot of the tie comprises the holder parts A and B and the section 16 of the necktie.

The necktie and the parts A and B are securely held against slipping through the gripping action of the bulges 4, 11, and 12 which are in registration with each other when the tie has been adjusted as shown in Fig. 9. The extension 9 serves as a convenient surface upon which to exert pressure when pushing the part B into the part A. Ordinarily the section 16 of the tie will be the first part to become soiled from handling, and it is obvious from the above explanation that this section can be easily replaced by a fresh sec-

tion for use with the remaining parts of the original tie, as mentioned at the beginning of this specification.

I claim:

1. A necktie and holder assembly in which the holder and the necktie each consist of two separate parts, the two parts of said holder being of similar conformation and adapted to be engaged one within the other, the outer of said parts having a cut-out portion and retaining elements comprising inwardly bent portions at the edges of said cut-out portion, the inner of said parts being bent to provide parallel sections and having an opening in registration with the cut-out portion of the outer part, one of said parallel sections having a straight edge and the other of said parallel sections having a curved edge, one part of said necktie being shaped to conform to the outer surface of the outer part of said holder and engaged therewith, the other part of said necktie having a wide and a narrow portion and an offset separating said wide and narrow portions, some of the wide portion of said tie being gripped between the outer and inner parts of said holder and some of the narrow portion of said tie being gripped between the parallel sections of the inner part of said holder, the entire assembly being held in gripping engagement by the retaining members of the outer part of said holder so that said holder and the portions of said necktie engaged therewith comprise the knot of the completed tie.

2. A necktie and holder assembly in which the holder and the necktie each consist of two separate parts, the two parts of said holder being of similar inverted, truncated conical conformation and adapted to be engaged one within the other, the outer of said parts having a longitudinal cut-out portion and inwardly extending flanges at the edges of said cut-out portion, the inner of said parts being bent longitudinally to provide an outer section and an element parallel therewith, said outer section and said element being spaced apart, said inner part of said holder having an opening in registration with the cut-out portion of said outer part and an extension across said opening, one part of said necktie being shaped to conform to the outer surface of the outer part of said holder and having its ends in engagement with the flanges of said outer part, the other part of said necktie having a wide and a narrow portion and an offset separating said wide and narrow portions, some of the wide portion of said tie being gripped between the outer and inner parts of said holder and some of the narrow portion of said tie being gripped between the outer section and parallel element of the inner part of said holder, the entire assembly being held in gripping engagement by said flanges so that said holder and the portions of the necktie engaged therewith comprise the knot of the completed tie.
